UNITED STATES PATENT OFFICE.

WILLIAM AMOS, OF PROVIDENCE, RHODE ISLAND.

CAR-SWITCH.

SPECIFICATION forming part of Letters Patent No. 448,570, dated March 17, 1891.

Application filed April 28, 1890. Serial No. 349,162. (No model.)

To all whom it may concern:

Be it known that I, WILLIAM AMOS, a citizen of the United States, residing at Providence, in the State of Rhode Island, have invented a new and useful Improvement in 5 Car-Switches, of which the following is a specification.

The nature of my invention consists in the improved construction and arrangement of 10 the operating-levers of the switch, as herein-after fully set forth.

Figure 1 represents a plan view of the road-bed and of the forward platform of the car, and shows the mechanism of a double switch, 15 the cover of the sunken box for holding the switch-operating levers being removed. Fig. 2 represents an elevation of a portion of the forward end of the car and a vertical section of the sunken box for holding the switch- 20 operating levers. Fig. 3 is a plan view of the road-bed, showing the mechanism of a single switch, the cover of the sunken box which holds the switch-operating levers being removed.

In the accompanying drawings, Figs. 1 and 25 2, A represents the forward end of the car; B B, the straight track; C C, the track turning to the right hand and D D the track turning to the left. The pivoted switch- 30 tongues E E' are attached to a bed-plate F, which is preferably cast integral with the sunken box G, which protects the switch-operating levers. The left-hand switch-tongue E is provided with a stud a, which extends 35 downward through a suitable opening in the plate F, and to the lower end of the stud a is pivoted the bar b, to the opposite end of which is pivoted the horizontal bell-crank lever c, and to its middle portion is pivoted the re- 40 versely-set horizontal bell-crank lever d, the said bell-crank levers being also pivoted to the bridge e at the pivot-studs f, and from the short arm g of the horizontal bell-crank lever c connection is made to the short arm h 45 of the vertically-arranged bell-crank lever i by means of the connecting-rod j, the outer end of the bell-crank lever i being provided with the engaging-head k, which projects upward through a suitable opening l in the 50 cover H of the box G; and from the short arm g' of the horizontal bell-crank lever d connection is made to the short arm h' of the vertically-arranged bell-crank lever i' by 55 means of the connecting-rod j', the outer end of the bell-crank lever i' being provided with the engaging-head k', which projects upward through a suitable opening in the cover H, so that when the slightly-projecting head k is pressed down the switch-tongue E will be moved outward to the position shown in Fig. 1, and when the head k' is pressed down the switch-tongue E' will be thrown inward, so as to 60 guide the forward wheels of the car A onto the left-hand track D D, the downward movement of one of the said heads causing a corresponding upward movement of the other. The right-hand switch-tongue E' is also provided with a stud a, which extends downward through a suitable opening in the plate F, and to the lower end of the stud a is pivoted 65 the bar b', to the opposite end of which is pivoted the horizontal bell-crank lever m and to the middle portion is pivoted the reversely-set horizontal bell-crank lever n, the said bell-crank levers being also pivoted to the bridge 70 e at the pivot-studs f, and from the short arm o of the horizontal bell-crank lever m connection is made to the short arm p of the vertically-arranged bell-crank lever q by means of the connecting-rod r, the outer end of the 75 bell-crank lever q being provided with the engaging-head s, which also projects upward through a suitable opening in the cover H, and from the short arm o' of the horizontal bell-crank lever n connection is made to the short arm p' of the vertically-arranged bell-crank lever q' by means of the connecting-rod r', the outer end of the bell-crank lever q' being provided with the engaging-head s', which also projects upward through a suitable opening in the cover H, so that when the slightly-projecting head s is pressed down the switch-tongue E' will be moved outward to the position shown in Fig. 1, and when the head s' is released and the head s' is pressed 80 down the switch-tongue will be thrown inward, so as to guide the forward wheels of the car A onto the right-hand track C C, the downward movement of one of the said heads causing a corresponding upward movement 85 of the other.

To suitable brackets I, at the under side of the platform of the car A, are pivoted the levers J, K, and L, which at their forward ends

- are pivoted to the rods *t*, having at their upper ends the pedal-plates *J'*, *K'*, and *L'*, respectively, and between each of the said pedal-plates and the floor of the platform *M* is placed a spiral spring *u*, which serves to hold the lever in an elevated position. At a forward and downwardly inclined position upon the levers *J*, *K*, and *L* are placed the rollers *v* *v'* *v²*, respectively, which are each adapted to engage with two of the upwardly-projecting heads *k* *k'* *s* *s'*, so that when the driver places his foot on the left-hand pedal *J'* and presses downward upon the same against the upward action of the spring *u*, the roller *v* being adapted to press upon the shoes *k* and *s*, will serve to throw the switch-tongue *E* inward and the switch-tongue *E'* outward, so that the car will pass safely onto the track *D D*, and when the driver places his foot upon the right-hand pedal *L'* the roller *v²* will press upon the shoes *s' k*, and thus move the switch-tongue *E'* inward and the switch-tongue *E* outward, thus causing the car to pass safely onto the track *C C*, and when the driver presses with his foot upon the middle pedal *K'*, then the roller *v'* will engage with the shoes *s k*, which will cause the tongues *E* and *E'* to be moved in opposite directions to the position shown in Fig. 1, in which the car will be safely directed along the main track *B B*. The bell-crank levers *i i'* and *q q'* are pivoted to the bottom of the box *G*, as shown in Fig. 2, and a stop *w* is provided to prevent excessive downward movement of the engaging-heads by contact with the wheels of passing vehicles.
- A single switch operating to throw the car from the main line to a single branch track is shown in Fig. 3, in which the connection between the switch-tongue *E'* and the engaging-heads *s s'* is made, as above described, for turning the car to the right-hand track *C C*, the heads *s* and *s'* being operated by means of separate pedal-levers, as before.
- The pedal-levers *J*, *K*, and *L* are so pivoted to the car that the engaging-point of the roller will be below and at about forty-five degrees

in advance of a vertical line passing through the pivot of the lever, in order that the shock of engagement with the switch-operating heads will be sustained by the lever without injurious upward reaction against the foot of the driver.

I claim as my invention—

1. The combination of the pivoted switch-tongues at opposite sides of the main track, the pivoted bars, the opposite bell-crank levers pivoted to the said bars, the vertically-arranged bell-crank levers provided with an engaging-head, and the connecting-rods which serve to connect the vertically-arranged bell-crank levers with the horizontal bell-crank levers, the car provided with the pedal-levers having elongated rollers or tappets to engage with the two adjacent projecting heads, substantially as described.

2. The combination, with the pivoted switch-tongue at one side of the main track, of the pivoted bar, the oppositely-directed bell-crank levers pivoted to the pivoted bar, the vertically-arranged bell-crank levers provided with an engaging-head, the connecting-rods which serve to connect the vertically-arranged bell-crank levers with the horizontally-arranged bell-crank levers, and the car provided with pedal-levers, which are pivoted to the car and provided with an engaging point or roller located at a forward and downward angle from a vertical line passing through the pivoting-point, substantially as described.

3. The combination of the pivoted switch-tongue at one side of the main track, the engaging-heads oppositely connected with the pivoted switch-tongue, and the car provided with the pedal-levers, which are pivoted to the car and provided with an engaging point or roller located at a forward and downward angle from a vertical line passing through the pivoting-point, substantially as described.

WILLIAM AMOS.
